BABY TEETHER, PACIFIER AND GUM SOOTHER

Murry Herbst, 266—16 78th Ave.,
Floral Park, N.Y. 11004

Filed Mar. 11, 1970, Ser. No. 21,864

Term of patent 14 years

Int. Cl. D24—05

U.S. Cl. D83—8

FIG. 1.

FIG. 2.

FIG. 3.

FIG. 4. FIG. 5.

FIG. 6.

FIG. 7.

FIG. 1 is a perspective view of a baby teether, pacifier and gum soother showing my new design;

FIG. 2 is a side elevational view looking at the front thereof;

FIG. 3 is a side elevational view looking at the back thereof;

FIG. 4 is an end view looking at the right side of FIG. 2;

FIG. 5 is an end view looking at the left side of FIG. 2;

FIG. 6 is a top plan view thereof; and

FIG. 7 is a bottom plan view thereof.

I claim:

The ornamental design for a baby teether, pacifier and gum soother, substantially as shown.
